(57) **CLAIM**

The ornamental design for a portable ultrasound device, as
shown and described.

DESCRIPTION

FIG. 1 is a front and right perspective view of a portable
ultrasound device according to an embodiment;

FIG. 2 is a rear and left perspective view thereof;

FIG. 3 is a rear and right perspective view thereof;

FIG. 4 is a front and left perspective view thereof;

FIG. 5 is a front view thereof;

FIG. 6 is a left side view thereof;

FIG. 7 is a right side view thereof;

FIG. 8 is a rear view thereof;

FIG. 9 is a top view thereof; and,

FIG. 10 is a bottom view thereof.

The broken lines in the drawing views are directed to environmental
subject matters and form no part of the claimed
design.
